UNITED STATES PATENT OFFICE.

WILLARD H. KEMPTON, OF HARTFORD, CONNECTICUT, ASSIGNOR TO THE JOHNS-PRATT COMPANY, OF HARTFORD, CONNECTICUT, A CORPORATION OF CONNECTICUT.

TROLLEY-WIRE HANGER.

No. 926,258.

Specification of Letters Patent.

Patented June 29, 1909.

Application filed December 12, 1908. Serial No. 467,240.

To all whom it may concern:

Be it known that I, WILLARD H. KEMPTON, a citizen of the United States, residing at Hartford, in the county of Hartford, 5 and State of Connecticut, have invented a new and useful Trolley-Wire Hanger, of which the following is a specification.

This invention relates to a hanger which is designed to mechanically grip and support a trolley wire, messenger wire, or other wires or cables used in overhead electric 10 railway systems.

The object of the invention is to provide a strong hanger with simple parts which 15 are cheap to manufacture and easy to assemble, and which is so constructed that the heavier the weight or downward strain, the tighter the clamp will grip and hold the wire or cable.

20 Figure 1 of the accompanying drawings shows a side view of a hanger which embodies the invention. Fig. 2 shows a side elevation of the toggle which is designed to hold the clamp plates together. Fig. 3 is a central vertical section of the hanger. Fig. 4 is an end view of the hanger. Fig. 5 is a perspective view of the toggle holding block which is located between the clamping plates. Fig. 6 is a perspective 25 view of one of the toggle links. Fig. 7 is a perspective view looking at the inside of one of the clamping plates. Fig. 8 shows a vertical section of the hanger with the supporting rod arranged so as to permit of a vertical yielding of the hanger and trolley wire. Fig. 9 shows a central vertical section of a hanger with the holding rod arranged in another manner which allows 30 a vertical yielding of the hanger and wire.

40 The hanger illustrated is particularly designed to clamp and hold a grooved trolley wire 1, although the invention is applicable for suspending trolley wires having other cross sectional shapes, and for supporting other wires and cable of an electric system.

The clamping plates 2 which are shown in the drawings are formed similar in outline, of any suitable metal, with jaws 3 along their lower edges shaped to grip a 45 grooved trolley wire, and with recesses 4 at their upper edges which permit the passage through them of the supporting rod 5. Between the clamping plates, which are hol-

low for the purpose, is a block 6 having a threaded perforation into which the end of 55 the supporting rod is screwed.

The toggle links 7 of the hanger shown, extend through openings 8 in the clamping plates and are pivoted on a pin 9 which is held by ears projecting from the block. The 60 outer ends of the toggle links are provided with bars 10 that, when the parts are assembled, rest in recesses 11 in the outer faces of the clamping plates. A nut 12 is turned upon the threaded end of the supporting 65 rod in such manner that it may be screwed down against the upper edges of the clamping plates.

After a trolley or other wire or cable has been located between the clamping plates 70 the nut is turned down against the upper edges of the plates. This draws the block and inner ends of the toggle links upwardly between the plates, which action closes the toggles and causes the toggle bars on the 75 outside to pull the clamping plates tightly together. The harder the nut is turned down on the supporting rod against the edges of the clamping plates, the tighter the 80 toggle bars draw the plates together and cause them to grip the wire or cable between them. The weight of the suspended 85 wire itself, when the clamping plates are engaged with it, tends to draw the plates down with relation to the supporting rod, and the block with which it is connected, 90 and this causes the toggle to draw and hold the plates together. The parts cannot be disengaged and the wire released until the nut is loosened. But when the nut is loosened the toggle is relieved so that the plates 95 can be separated and disengaged from the wire.

For the purpose of allowing the hanger to yield, the supporting rod can be provided 100 with a head 13, which may be arranged in a casing 14 that is provided with a nut 15, into which the end of a continuation of a hanger rod 16 may be screwed, as shown in Fig. 8. Another method of providing for a vertical 105 yielding of the hanger and wire is to extend the shank 17 of the toggle block upwardly between the upper edges of the clamping plates and through the nut 18, as shown in Fig. 9. In this case the nut is screwed upon the shank of the toggle block until it bears

against the upper edges of the clamping plates, which action causes the toggle to draw the plates together. The shank of such a toggle block may be provided with a 5 socket 19 adapted to receive a head 20 of the supporting rod 21. A cap 22 may then be screwed upon the end of the shank of the block so as to hold the head of the supporting rod in the socket.

10 The invention claimed is:

1. A hanger having clamping plates, a toggle block located between the plates, a support for said block, toggle links carried by the block and adapted to draw the plates 15 together, and a nut arranged to force the plates and the toggle in opposite directions, whereby the toggle will draw the plates together.

2. A hanger having clamping plates, a 20 toggle block located between the plates, toggle links pivoted to the block and extending through the plates, means connected with the toggle links and bearing against the outer sides of the plates, and means for forcing the toggle block and the plates in opposite 25 directions with relation to each other.

3. A hanger having clamping plates, a toggle block located between the plates, a toggle pivoted to the block and adapted to 30 draw the plates together, and means for drawing the toggle block upwardly with relation to the plates.

4. A hanger having clamping plates, a toggle engaging and adapted to draw the 35 clamping edges of the plates together, and

means for causing the toggle to draw the plates together.

5. A hanger having clamping plates, a block located between the plates, a toggle pivoted to the block and adapted to hold 40 the plates together, a rod adapted to support the toggle block, and a nut threaded on said rod and adapted to force the plates and the toggle block in opposite directions.

6. A hanger having a pair of plates, a 45 block located between the plates, a toggle pivoted to the block and extending through the plates and bearing on their outer surfaces, a rod connected with the block and extending between the plates, and a nut 50 threaded upon the rod and adapted to force the plates and the block in opposite directions.

7. A hanger having clamping plates, a toggle hinged between the plates and having 55 bars bearing against the outer surfaces of the plates, and means for causing the toggle to draw the plates together.

8. A hanger having clamping plates, a toggle engaging and adapted to draw the 60 clamping edges of the plates together, means for causing the toggle to draw the plates together, and a support connected to and having a limited vertical movement independently of said toggle actuating means.
